BINDER

Nathan August, Jr., Newark, N. J.

Application July 22, 1944, Serial No. 546,168

1 Claim. (Cl. 129—16)

This invention relates to improvements in binders, and more particularly to a binder which is designed to hold a plurality of leaves, or index or reference cards, in a positive fashion which will permit of ready access to any selected card, and is of simple and positive construction and operation.

These and other advantageous objects, which will later appear, are accomplished by the structure shown and described in the accompanying drawing, in which:

Fig. 1 is a top plan view of the binder of my invention, showing a plurality of cards held therein;

Fig. 2 is a longitudinal vertical sectional view thereof taken on line 2—2 of Fig. 1 in the direction of the arrows, and

Fig. 3 is an exploded perspective view of parts of the apparatus shown in Figs. 1 and 2 bearing corresponding reference numerals.

As shown in the drawing, the binder of my invention comprises a base plate 10 provided with upstanding front and rear walls 11 and 12, said walls terminating in angularly directed ledge portions 14 and 15, respectively. The loose leaves or cards 16 which are positioned in the binder of my invention preferably rest upon a pair of parallel spaced rails 17 which, as shown in the drawing, are preferably in the form of wire rods having their ends curled to describe loops 18 for the reception of the means 19 for securing said rods to the walls of the binder. A pair of cover members 20 and 21, which are preferably made of substantially rigid material such as that used to form book covers, are positioned on the rails 17, the loose leaves or cards 16 being interposed between said covers and on the rails. The lower end 22 of the cover 20 is angularly directed and interposed or inserted between said front ledge 14 and the ends of the rails, the parts described being secured together by clamping means 19. The rear cover 21 has the lower edge 23 thereof angularly directed and positioned on the rails 17, an angle plate 24 being positioned on the lower edge 23 of the rear cover 21, a second angle plate 25 being positioned beneath the rails 17 in registry with the lower cover edge 23. The parts described are secured together as shown in Fig. 2 by means 26 which will permit of the locking of the cover edge 23 to the rails 17 at any predetermined point and will permit of the unlocking thereof for adjustment to compensate for the removal or insertion of loose leaves or cards 16 between the covers 20 and 21. The rear cover 21 may be further provided with a strap or the

like 27 provided at one end with means such as a glove fastener element 28 adapted to have complementary engagement with a glove fastener stud or the like on the front cover 20, to close the binder and provide a convenient means for carrying the same. The other end of said strap 27 is secured to the rear cover 21 by any means which will permit of the adjustment of the length of said strap protruding from the rear cover 21. Said means may comprise a buckle 29 or the like as shown in Fig. 3 which will permit of the relative adjustment of the protruding length of the strap 27 extending over the rear cover 21. The means 19 and 26 for locking the front and rear covers to the rails 17 may be of any desired or convenient configuration and may, for example, as shown in Fig. 2, comprise bolt and nut members 30 and 31, bolt and nut members 32 and 33 or any other desired or convenient interengaging members.

It will be apparent from an inspection of the drawing that the angle plates 24 and 25 and the lower edge portions 22 and 23 of the front and rear covers, and the front ledge 14 of the binder, are provided with suitable apertures for the reception of the described locking means, and that the angle plate 24 is provided with recessed portions 34 for the reception of the rods 17 to facilitate the interlocking of the parts as above described.

The loose leaves or cards 16 may be positioned on the rails 17 and may, if desired, be provided with lower slots 35 to receive said rails as shown in Fig. 2, or the lower edges of said loose leaves or cards 16 may simply rest on said rails, the ends of said loose leaves or cards being held against lateral displacement by the side walls 37 of the binder, said side walls for this purpose preferably protruding above the front and rear ledges 14 and 15 of the binder. When the cards or loose leaves 16 are provided with slots 35 for the reception of rails 17 the sides of the binder 11 may be left open. The elements 30 and 33 of the locking means for securing the front and rear covers to the rails 17 may be of any desired ornamental or utilitarian configuration and may, as shown in Fig. 2, be generally elongated and dome-shaped so as to provide abutting stop means for the front and rear covers 20 and 21 to limit the movement of said covers in a forward direction to the line A and in a rearward direction to the line B at Fig. 2. The rear ends of the rails 17 may be secured to the rear ledge 15 of the binder by bolt and nut means 19 passing through apertures in said rear ledge 15 and

through the loops 18 of said rails 17 as shown in Fig. 2.

In operation, when it is desired to insert loose leaves or cards 16 between the covers 20 and 21, the locking means 26 are manipulated to loosen the same and to thereby permit the rear cover 21 to be adjusted on the rails to the desired position thereon and then, by simple tightening the locking means 26, the rear cover will be firmly held in the desired position. It will be apparent that by the arrangement described, the loose leaves 16 will be held in a position which permits immediate access to be had at all times thereto for reference, removal, or replacement purposes, and that the structure described provides simple and positive means for adjusting the relative position of the rear cover 21 to compensate for variations in the number of cards or other data inserted between the cover members. In this connection, the invention is not limited to the use of the device for holding loose leaves or cards, but may be used in any situation for which a device for the structure described and shown is adapted. It will be noted further that the cover 21, being preferably made of a substantially rigid yet slightly flexible material, it is merely necessary to slightly disengage the locking means 26 to permit the rear cover 21 and associate parts to be moved on the rails 17 to the desired position and then, by simple slightly tightening of the locking means, the rear cover 21 may be positively posi-

tioned on said rails. The base plate 10 may further be provided with a plurality of resilient leg members 36 or the like, to preclude the possibility of scratching any surface on which the same may be positioned. The various parts described may be made of metal, plastics or other suitable materials.

Having thus described my invention, what I claim as new and desire to secure by Letters Patent, is:

A binder for holding articles, comprising a base plate, front and rear walls integral with said base plate, said front wall terminating in an angularly directed ledge portion, a pair of rail members secured to said walls in parallel spaced relation, a cover member provided with an angularly directed lower end, said angularly directed end being interposed between the ledge of the front wall and the rails, means to removably secure 15 said lower end and rails together, a rear cover member provided with an angularly directed lower edge positioned on the rails, a plate positioned on the angularly directed lower edge of said rear cover, a second plate, means engaging 20 said plates to lock said plates and said lower edge to the rails and to permit of the unlocking thereof for adjustment to compensate for removal or insertion of loose leaves or cards between said 25 cover members, and means to removably secure 30 the rails to the rear wall of the base plate.

NATHAN AUGUST, JR.
